UNITED STATES PATENT OFFICE.

GUSTAV SANDBLOM, OF NEW YORK, N. Y.

MACHINE FOR TWISTING FLAT METAL BARS.

SPECIFICATION forming part of Letters Patent No. 777,224, dated December 13, 1904.

Application filed August 27, 1904. Serial No. 222,392. (No model.)

To all whom it may concern:

Be it known that I, GUSTAV SANDBLOM, a citizen of Sweden, residing at New York city, (Queens,) county of Queens, and State of New York, have invented new and useful Improvements in Machines for Twisting Flat Metal Bars, of which the following is a specification.

This invention relates to a machine for providing a flat metal bar with a bent section between its ends, bars of this character being used for bridle-irons and other purposes.

In the accompanying drawings, Figure 1 is a plan of the principal part of my improved machine; Fig. 2, a longitudinal section thereof on line 2 2, Fig. 1; Fig. 3, a front elevation; Fig. 4, a detail section on line 4 4, Fig. 1; Fig. 5, a detail of one of the bearing-blocks and abutments, and Fig. 6 a perspective view of the twisted bar formed by the machine.

20 The object of the invention is to provide a flat bar A, Fig. 6, with a turned-down section A', which merges into the body of bar A by the twisted sections A².

The letters a a represent a pair of parallel standards that support at one end a bed-plate b, having a pair of slots b' and a rib b². To bed-plate b are adjustably secured in front of rib b² a pair of bearing-blocks c, the distance between which may be regulated to conform substantially to the distance between the outer corners A³ of the twisted sections A². The connection between bearings c and bed-plate b is effected by a groove and a key b³, which is arranged parallel to rib b². After the bearings c have been properly spaced they are locked in position by set-screws c' entering one of a number of tapped openings b⁴ of plate b and by clamp-screws c² pressing upon key b³. The screws c² also serve to connect a top plate d to each of the bearings c, such top plate overhanging the rear of the bearing, Figs. 2 and 4. At its inner end each bearing c is recessed to accommodate a tapering abutment e, fulcrumed to the bearing at e'. During the bending operation the abutments e are subjected to considerable strain, under which they will slightly turn inward and correspondingly relieve the inner corners of bearings c. Between the bearings c there projects through each of the slots b' an inclined gripper f, the

upper hook-shaped head f' of which is adapted to engage the upper edge of bar A vertically above the inner corner A' to be formed on the bar.

The grippers f are operated in the following manner: g is a power-shaft carrying crank-disk g', the wrist-pin g² of which engages one end of pitman h. The other end of this pitman is connected at h' to the lower arms of a pair of diverging elbow-levers i, turning on spindle j, which is hung in bearings b⁵ of plate b. The upper arms of elbow-levers i are slotted to accommodate the shanks of grippers f, Fig. 3, which are pivoted thereto at f², Fig. 4. The rotation of the power-shaft g will thus 65 by elbow-levers i cause a simultaneous forward and downward motion of grippers f. By this action the bar A is shaped in the manner desired, the turned-down section A' being forced into an inclined surface-groove b⁶ of 70 bed-plate b. This groove permits the section A' to be bent downward slightly in excess of ninety degrees, so that it will assume its correct position by the back spring of the metal. The grippers f are held in an upright position 75 during the introduction of the work-piece by chains f³ and counterweights f⁴. The lower edge of bar A is engaged by a pair of hooks k, that are arranged below grippers f and project through the slots b' of plate b. Each hook 80 is fulcrumed to plate b at b' and is provided with a shank k', carrying an adjustable counterweight k².

The operation is as follows: The bar A is placed on edge upon table b between rib b² 85 and bearings c, its bottom edge being engaged by hooks k. The grippers f are turned backward against action of counterweights f⁴, and are thus brought into engagement with the upper edge of bar A. By now rotating shaft 90 g the grippers are drawn downward and forward to bend the section A' into a substantial horizontal position in the manner desired. During the commencement of this action the hooks k will hold the lower edge of bar A 95 against forward displacement and prevent the bar from becoming bulged.

What I claim is—

1. In a machine for twisting flat metal bars, the combination of a bed-plate with a pair of 100

bearings having recessed inner ends, tapering abutments pivoted to such ends, and a pair of hook-shaped grippers intermediate the bearings, substantially as specified.

- 5 2. In a machine for twisting flat metal bars, the combination of a bed-plate with a pair of bearings, a pair of hooks adapted to engage the lower edge of the work-piece, and a pair of grippers adapted to engage the upper edge
10 of said work-piece, substantially as specified.
3. In a machine for twisting flat metal bars, the combination of a bed-plate having a rib,

with a pair of bearings adjustably secured to the bed-plate, a top plate, a pair of movable abutments at the inner edges of the bearings, and grippers and hooks intermediate the bearings, substantially as specified. ¹⁵

Signed by me at New York, (Manhattan,) N. Y., this 25th day of August, 1904.

GUSTAV SANDBLOM.
